UNITED STATES PATENT OFFICE.

JOSEPH KUNKLE, OF INDIANAPOLIS, INDIANA.

IRONING BOARD.

Application filed April 6, 1925. Serial No. 21,189.

To all whom it may concern:

Be it known that I, JOSEPH KUNKLE, a citizen of the United States, residing at Indianapolis, in the county of Marion and State of Indiana, have invented certain new and useful Improvements in Ironing Boards, of which the following is a specification.

My said invention relates to a folding ironing board and it is an object of the same to provide a device of this character which shall be simple and inexpensive in construction, rigid and durable in use and which may be quickly folded so as to occupy only a small space.

Referring to the accompanying drawings, which are made a part hereof and on which similar reference characters indicate similar parts,

20 Figure 1 is a perspective of my device in open position,

Figure 2, a vertical longitudinal section,
Figure 3, a similar section of the device

in folded position, and
25 Figure 4, a detail of parts shown in the
other figures.

In the drawings reference character 10 indicates what may for convenience be referred to as the table section on which are spread the clothes to be ironed. This table is secured by one or more hinges 11 to a cross bar 12 fixed at its ends to posts 13 which rest on the floor and are secured together at their lower ends by means of a cross bar 14.

A hinge 15 is attached to the lower part of the cross-bar 12 and serves to secure a brace 16 in pivoted relation to the hinge. A pair of braces 17 are pivotally secured at their upper ends to table 10 by means of hinges 18 and have openings approximately midway of their length registering with an opening at 19 in the brace 16 to receive a pin or bolt 20 by means of which the braces are held against collapsing. The parts adjacent the opening are reenforced in conventional manner by means of strips of sheet metal or other suitable material, as indicated at 21. At their lower ends the braces 17 are connected by a U-shaped strip of metal 22 which has its extremities bent at an obtuse angle so as to lie flat upon the cross bar 14. A plurality of pins or lugs 23 extend upward through orifices in the bent parts of the member 22 and these pins are provided with registering apertures to

receive a pin 24 which extends over the member 22 and holds the lower end of braces 17 in place on the cross-bar 14.

The brace 16 is provided at 25 with a staple or analogous holding device to which a rod 26 is pivotally connected. At its free end the rod has an eye fitting over the middle one of lugs 23, the pin 24 passing above said eye and holding the rod 26 in place at that end whereby the rod provides bracing means for holding the members 14 and 16 in correct relative position. An apertured lug 27 at the upper end of the brace 16 serves to receive the eye when the board is in folded position and a pin is located in the aperture to prevent disengagement of the eye of said rod 26.

It will be obvious to those skilled in the art that various changes may be made in my device without departing from the spirit of the invention and therefore I do not limit myself to what is shown in the drawings and described in the specification but only as indicated in the appended claims. 80

Having thus fully described my said invention, what I claim as new and desire to secure by Letters Patent is:

1. A folding ironing board comprising a table section, a pair of posts for supporting the same, cross-bars connecting said posts at their upper and lower ends, pivotal connections between the upper cross-bar and the rear end of the board, a pair of braces pivotally connected to the board, a U-shaped metallic strip connecting said braces near their free ends and having its extremities bent to rest on the lower cross-bar, apertured lugs on the cross-bar adapted to enter orifices in said extremities, a pin passing through the apertures in such lugs for holding the braces in position, a brace pivotally connected to the upper cross-bar and extending forward underneath the ironing board said brace crossing the first-named braces, and a rod pivotally connected to the last-named brace adjacent its forward end said rod having an eye at its free end, an apertured lug in line with said first-named lugs on the lower cross-bar to receive said eye said pin passing through said aperture above said eye on the rod, substantially as set forth. 85 90 95 100 105

2. A folding ironing board comprising a table section, a support adjacent one end thereof pivotally connected to the table to fold up underneath the same, a brace pivot-

ally connected to the table and detachably connected to said support adjacent its lower end, an apertured lug on the support engaging an aperture in said brace, a lug on said support having an aperture in line with that of the first-named lug, a brace pivoted adjacent one end of the table and cooperating with the first-named brace for supporting the table, a rod connected to the last-named brace said rod having an eye embracing the last-named lug, and a pin passing through

the apertures in said lugs for securing the rod and the first-named brace in the open position of the table, substantially as set forth.

15

In witness whereof I have hereunto set my hand and seal at Indianapolis, Indiana, this 1st day of April, A. D. nineteen hundred and twenty-five.

JOSEPH ^{his} X KUNKLE. [I. S.]
